(57) **CLAIM**

The ornamental design for a reversible ramp, as shown and described.

DESCRIPTION

FIG. 1 is an isometric view of a reversible ramp; FIG. 2 is a right view of the reversible ramp of FIG. 1; FIG. 3 is a left view of the reversible ramp of FIG. 1; FIG. 4 is a top of the reversible ramp of FIG. 1; FIG. 5 is a bottom view of the reversible ramp of FIG. 1; FIG. 6 is a front view of the reversible ramp of FIG. 1; FIG. 7 is a rear view of the reversible ramp of FIG. 1; and, FIG. 8 is an isometric view of section 8-8 of FIG. 1. The reversible ramp is shown with a symbolic break in its length. The appearance of any portion of the reversible ramp between the break lines forms no part of the claimed design. The broken lines in the drawings depict portions of the reversible ramp that form no part of the claimed design.
